METALLIC-VAPOR LAMP.

1,244,121.

Specification of Letters Patent. Patented Oct. 23, 1917.

Application filed February 2, 1914. Serial No. 815,869.

To all whom it may concern:

Be it known that I, WALther NERNST, a subject of the German Emperor, residing at Berlin, Germany, have invented a new 5 and useful Improvement in Metallic-Vapor Lamps, of which the following is a specification.

My invention refers to metallic vapor lamps, that is to lamps containing some suitable metal and provided with a space within 10 which the vapor of such metal becomes incandescent when the lamp is suitably actuated by the necessary electric current.

The object of my invention is to provide a 15 metallic vapor arc lamp in which that part of the lamp which furnishes illumination during its operation, contains, before ignition, gases (or air) which, by reason of the seething and boiling of the metal, for instance, mercury, during said operation, are driven completely out of the illuminating space, into an auxiliary chamber forming a 20 part of said space, or in the case of air into the atmosphere, and are prevented from re-entering by the continued boiling of the metal, but when the lamp is extinguished, again enter into the illuminating space.

Before the lamp is started, the illuminating space contains any suitable gas, for instance 30 argon, or it may be filled with air and in such latter case, this space communicates with the atmosphere. For the purpose of ignition the vapor producing metal is caused to actively give off said vapor in 35 any convenient manner. For this purpose mercury constitutes a very suitable metal, although the invention is by no means limited to mercury, and for convenience of description mercury, will be referred to as 40 the metal used in the particular embodiments therein specifically described. Other metals which may be used are zinc, cadmium and alloys of mercury with these metals, lead, etc., especially when closed 45 lamps, filled with neutral gases are used. This vapor crowds out the gases or air which are in the illuminating space so that the plane of demarcation between the mercury vapor and the gas or air lies entirely out- 50 side of the illuminating space. The lamp must be provided with an auxiliary space or chamber which is filled in that part adjoining the illuminating space with mercury vapor and in its opposite part with the gases

referred to or with air; this space acts as a 55 cooler.

The cooling effect must not be too great in order that the vapor column between the illuminating space and the gases crowded out, may be long enough to prevent the back 60 diffusion of gases toward the illuminating space; it ought, however, not be too small thus avoiding too great compression of the crowded out gases and preventing escape of the mercury vapor in the case of such lamps 65 as communicate with the atmosphere.

The heating of the mercury can be accomplished in any known manner either by means of a flame or by electrical means.

In the cases of lamps which contain neutral 70 gases which neither combine with or attack the vapor forming metal nor the anode, which latter may be made of other metal, vaporization can be started in such a way that an arc is first started in said 75 gases (rare gases such as argon and neon are especially suitable for this), which arc will then without any special heating arrangement, supply sufficient heat to maintain the necessary vaporization and drive back the 80 gases. The starting of the arc may be done in any wellknown manner, for instance by tilting the lamp as is done in the case of Cooper-Hewitt lamps.

In lamps which are provided with their 85 own special heating arrangement such arrangement may be either wholly or partially dispensed with as soon as the arc becomes stable and is itself able to compensate for the loss of heat.

In the drawings Figure 1 represents one 90 form of lamp embodying my invention and Fig. 2 and Fig. 3 modified forms thereof.

Referring to Fig. 1 the illuminating tube has free communication with the atmosphere. The cooler *k* is an upwardly directed tube which has an expansion near its top; the condensed metal drops back toward the mercury electrode *b*. The preliminary heating before lighting, which may be started 95 by tilting the tube in the usual way, takes place either at electrode *a* or at electrodes *a* and *b*. The illuminating space, as also the lighting tube proper is represented by *l*.

Lamps of this type, which communicate 100 with the atmosphere, may be filled with mercury at the place of use which makes the lamp easy of transport.

Fig. 2 illustrates a lamp, which is provided with a special space *c* through which the gases may be pressed by vaporizing the electrode material (mercury) and which is so shaped, *e. g.*, U-shaped, that mercury may then collect therein. This brings about a closure between the vapor space *l*, and the gas or air space which prevents excessive pressure fluctuations. *a* and *b* represent the electrodes, small vessels filled with mercury.

Fig. 3 illustrates a modified form of lamp which is closed off from the atmosphere and contains neutral gases as *e. g.*, attenuated argon or, better still, neon. The auxiliary space is indicated by *m* and the illuminating space, as before, by *l*. This lamp can be started up by a high tension impulse. In this lamp the cathode only consists of vaporizable material (mercury), for the anode, iron, etc., may be used.

The lamps are made from glass of very high heat resistance or better still of quartz.

When I say "normally" in the claims I refer to the condition of the lamp when it is not being operated.

I claim:

1. A metallic vapor lamp comprising a receptacle having an illuminating space, an auxiliary chamber communicating with said space, and a cathode of vaporizable metal, the space within the receptacle being normally at substantially atmospheric pressure.

2. A metallic vapor lamp comprising a receptacle having an illuminating space, an auxiliary chamber, a cooler which connects illuminating space and auxiliary chamber and normally has a free passage therethrough, and a cathode of vaporizable metal

within the receptacle, the free space within the entire receptacle being normally filled with a rare gas.

3. A metallic vapor lamp comprising a receptacle having an illuminating space, an auxiliary chamber, a cooler between illuminating space and auxiliary chamber and connected with both, and a cathode of vaporizable metal the space within the receptacle being normally at atmospheric pressure.

4. A metallic vapor lamp comprising a receptacle having an illuminating space, an auxiliary chamber, a normally open U-shaped connecting tube between illuminating space and auxiliary chamber, and a cathode of vaporizable metal, said U tube being adapted to collect condensed cathode metal, thereby becoming closed, during the operation of the lamp, the entire free space within the lamp being normally filled with an inert gas.

5. The improvement in the art of operating metallic vapor lamps having a vaporizable metal electrode which comprises starting the arc through a body of inert gas which is in contact with the cathode and in then causing said gas to be pressed substantially completely out of the illuminating space of the lamp by the vaporized cathode metal.

In testimony whereof, I have hereunto set my hand in the presence of two subscribing witnesses.

WALTHER NERNST.
